Kosea New York N.Y. and George P. Bowers and George Pratt of Boston (McAffe assigned to Avery, Bowers & Pratt) Letters Patent No 185, dated June 19th 1848

The schedule referred to in these letters Patent and making part of the same

To all whom it may concern:

Be it known that We, the Liam Powers, James C. Conklin and C. Brown of the ^{City} of New York, County and State of New York, and George P. Powers and Joseph Pratt of Boston in the County of Bristol and State of Massachusetts, have invented a new and ornamental design for stones, embracing a variety of ornamental designs combined in one; and we do hereby declare that the following is a full and exact description of the same reference being had to the annexed drawings making part of this specification.

Figure 1 represents the front view of the stone with the peculiar ornamental form thereof, and the arrangement of the several portions of the ornamental design. A is the body of the stone. B is the top, C the Gap, D the bottom. E the feet. F the fire door, ^{G the oven door.} H, I, K are original ornamental mouldings. Figure 2 is an original design to embellish the top of the stone. Figure 3 is an original ornament for the fire door. Fig. 4 is an original ornament for the oven door. Fig. 5 is a section of the ornamental moulding H. Figure 6 is a section of the ornamental moulding I.
Figure 7 is a section of the ornamental moulding J. Figure 8 is a section of the oranental moulding K.

That we claim as original and desire to
